UNITED STATES PATENT OFFICE.

F. ROBERT SEIDENSTICKER, OF MERIDEN, CONN., ASSIGNOR TO THE BRADLEY & HUBBARD MANUFACTURING COMPANY, OF SAME PLACE.

DESIGN FOR A LAMP-BRACKET.

SPECIFICATION forming part of Design No. 12,302, dated June 7, 1881.

Application filed April 30, 1881. Term of patent 7 years.

To all whom it may concern:

Be it known that I, F. ROBERT SEIDENSTICKER, of Meriden, in the county of New Haven and State of Connecticut, have invented a new Design for Lamp-Brackets; and I do hereby declare the following, when taken in connection with the accompanying drawing and the letters of reference marked thereon, to be a full, clear, and exact description of the same, and which said drawing constitutes part of this specification and represents a side view.

This invention relates to a design for bracket-arm for lamp-supports, for wall-brackets, or chandeliers; and it consists in the configuration and ornamentation as shown in the accompanying illustration.

From the socket or point of connection *a* springs a scroll-work, and from this scroll-work the arm extends downward in a curved shape to the key, thence upward, terminating at the lamp-base. On each edge of the arm is a plain band, each terminating in a scroll shape at the lamp-base, and from the outer scroll a floriated branch extends back onto the arm, and continues upon the side of the arm as a floriated vine. The end of the arm at the socket continues upward through the scroll-work, to make apparent firm connection therewith, and the scroll-work at the socket end is

enriched by floriated branches. At the point *30* which represents the key is a circular boss on the sides of the arm, with the representation of the key below and the rose-ornamentation above.

The lower section of the basket consists of *35* a bead, *b*, and cavetto *c* above, the basket above expanding in the shape of an inverted frustum of a cone, its upper edge formed in a series of scallops, all as shown in the accompanying illustration.

I claim—

1. The design for bracket-arm, consisting of the ornamental scroll-work springing from the socket, the curved arm extending therefrom to the lamp-base, with a scroll-work, and floriated branch or vine extending from the scroll-work at the end back onto the arm, as shown in the accompanying illustration. *45*

2. The design for lamp-bracket-arm fount-support, consisting of the lower section, composed of the bead *b* and cavetto *c*, with the upper section in inverted-frustum-of-cone shape, as shown in the accompanying illustration. *50*

F. ROBT. SEIDENSTICKER.
